CLAIM

The ornamental design for a bonding clamp, as shown and described.

DESCRIPTION

FIG. 1 is a top perspective view of a first embodiment of a bonding clamp;

FIG. 2 is a front view thereof;

FIG. 3 is a back view thereof;

FIG. 4 is a left-side view thereof;

FIG. 5 is a right-side view thereof;

FIG. 6 is a top view thereof;

FIG. 7 is a bottom view thereof; the unseen portion on the bottom surface of the top portion of the bonding clamp is planar and unornamented;

FIG. 8 is a top perspective view of a second embodiment of a bonding clamp;

FIG. 9 is a front view thereof;

FIG. 10 is a back view thereof;

FIG. 11 is a left-side view thereof;

FIG. 12 is a right-side view thereof;

FIG. 13 is a top view thereof; and,

FIG. 14 is a bottom view thereof; the unseen portion on the bottom surface of the top portion of the bonding clamp is planar and unornamented.

The dashed broken lines depict portions of the bonding clamp that form no part of the claimed design. The dot-dashed broken lines represent boundaries of the claimed bonding clamp and form no part of the claimed design.
